US0D1068869S

(12) **United States Design Patent** (10) **Patent No.:** **US D1,068,869 S**
(45) **Date of Patent:** **** Apr. 1, 2025**

(54) **MOLD**

(71) Applicant: **Spectrum Diversified Designs, LLC**,
Glenwillow, OH (US)

(72) Inventors: **Danwei Ye**, Solon, OH (US);
Andrianna Niebling, Tempe, AZ (US)

(73) Assignee: **Hologram Holdings I, Inc.**, San
Clemente, CA (US)

(**) Term: **15 Years**

(21) Appl. No.: **29/922,552**

(22) Filed: **Dec. 22, 2023**

(51) LOC (15) Cl. **15-07**

(52) U.S. Cl.

USPC **D15/90**

(58) **Field of Classification Search**
